INVENTOR:
Lucius O. Waldo
BY *David E. Gain,*
ATTORNEY.

UNITED STATES PATENT OFFICE.

LUCIUS O. WALDO, OF BELLINGHAM, WASHINGTON.

CAN-HANDLER.

1,288,769.

Specification of Letters Patent. Patented Dec. 24, 1918.

Application filed July 12, 1917. Serial No. 180,101.

To all whom it may concern:

Be it known that I, LUCIUS O. WALDO, a citizen of the United States, and a resident of Bellingham, in the county of Whatcom 5 and State of Washington, have invented certain new and useful Improvements in Can-Handlers, of which the following is a specification.

My invention relates to improvements in 10 can handling devices used by canners of food products, and the object of my invention is to produce a hand implement of strong, simple and light construction with which an operative may quickly transfer sealed cans 15 in regular order from one place to another and from one container to another without burning his hands, if the cans are hot, and without injuring the laquer or labels if the cans are freshly lacquered or labeled.

20 I attain this object by the mechanism illustrated in the accompanying sheet of drawings in which—

Figure 1 is a front elevation view of a one-row can handler, Fig. 2 is a plan view of the 25 same, Fig. 3 is an end elevation of Fig. 2, Fig. 4 is a front elevation view of a two-row can handler, Fig. 5 is a plan view of the same, Fig. 6 is an end elevation of Fig. 5, Fig. 7 is a plan view of a case of cans with 30 a two-row handler in engagement with the top layer of the same, Fig. 8 is a front elevation view of Fig. 7 and Fig. 9 is a side elevation view of a portion of the lower end of a can rollway, used as a magazine, with a 35 one-row handler in engagement with twelve of the lower cans on said rollway.

Similar characters refer to similar parts in the several views. Certain parts are broken away in order to show other parts 40 hidden thereby.

My device comprises head 1, regularly spaced prongs 2, 2, etc. and end prongs 2^a and 2^a attached to said head and projecting in the same plane at right angles from the front 45 edge of said head, and two handles 3, 3 attached to said head parallel with said prongs and to the rear of and in a plane above said prongs. Handles 3, 3 are attached to said head by shanks 3^a, 3^a. End 50 prongs 2^a, 2^a are preferably of one half the width of other prongs 2, 2, etc. In the construction used for the purposes of this specification, said prongs 2, 2, etc. and 2^a, 2^a are each made of a folded over wire with its 55 ends inserted in holes in the front edge of head 1.

The one-row handler shown in Figs. 1-3 and 9 holds twelve cans in one row, sides touching; while the two-row handler shown in Figs. 4-8 holds twelve cans in two rows 60 of six cans each, sides touching and rows end to end. It can be easily understood that my device can be constructed to hold other numbers and arrangements of cans than those shown. 65

In Fig. 9 cans A, A, etc. are shown on the lower end of a stopped rollway having bottom C, can stop C¹, back rail C², and front rail C³. Said front rail does not extend as far as can stop C¹. 70

In describing the way of using my can handler it is assumed that handles 3, 3 are in the hands of an operative. In Fig. 9 the one-row handler is shown in engagement with the lower twelve cans A, A, etc., on rollway C, prongs 2, 2, etc., and 2^a, 2^a having been caused to enter the voids between said cans A and bottom C. Then by lifting the handler the lower twelve cans A are carried in regular order with it and said cans are 80 retained on said handler in the manner shown in Figs. 1-3, where it may be noted the can's rims only are in contact with the prongs. 75

When using my two-row handler to remove cans from rollway C the six bottom cans are first lifted off to take their place on said prongs next to head 1 and then six more cans, which have moved down to the lower end of the rollway, are engaged with 90 said prongs and lifted from said rollway when the loaded handler appears as shown in Figs. 4-6. The said two-row handler is suited for filling case B of Figs. 7-8 with cans A, A, etc., or for removing said cans 95 from the same. In said figures the prongs are shown as supporting the top layer of cans A. 85

My device bears a row of filled cans, in close order sides touching, on a row of 100 prongs which are equally spaced and of equal width except the end prongs 2^a, 2^a. These are of one-half width to prevent their protruding beyond the cans and thus interfere with the easy entry of the fork-load of 105 cans into the case B. If the outside tines are one-half the width of the other tines and in the same plane, the best construction is had. The one-row handler is more particularly designed for filling and emptying 110 coolers used by fish canners. Here also the importance of not having the end prongs

project farther sidewise than the row of cans on the handler is apparent. When a rollway magazine is made for the exclusive use of two-row handlers the cans are caused 5 to be in two rows with cans end to end on the same.

The illustrated location of handles 3, 3 affords the operative good control of the device and the best advantage in handling the 10 weight of the cans.

Having thus fully disclosed my invention, what I claim as new and desire to secure by Letters Patent is—

1. In a can handler in combination, a head 15 and a plurality of spaced prongs in the same plane, attached to said head and projecting at right angles from the front edge of the

same, the end prongs being of substantially one-half the width of the other of said prongs.

2. In a can handler in combination, a head, a plurality of spaced prongs in the same plane, fastened to said head and projecting at right angles from the front edge of the same, the end prongs being of substantially one-half the width of the other prongs, and two handles attached to said head parallel with said prongs and above and to the rear of the same.

Signed at Bellingham in the county of 30 Whatcom and State of Washington this 22d day of June A. D. 1917.

LUCIUS O. WALDO.
